CLAIM

The ornamental design for a bed frame, as shown and described.

DESCRIPTION

FIG. 1 is a front perspective view of a bed frame showing my new design in a tilted configuration;
FIG. 2 is a front elevation view thereof;
FIG. 3 is a right elevation view thereof;
FIG. 4 is a left elevation view thereof;
FIG. 5 is a rear elevation view thereof; and,
FIG. 6 is a top plan view thereof.

The objects shown in dotted lines depict environment and form no part of the claimed design.

1 Claim, 6 Drawing Sheets
